UNITED STATES PATENT OFFICE.

MARK CANGEN, OF BROOKLYN, NEW YORK.

ARCH-SUPPORT FOR SHOES.

1,236,820.

Specification of Letters Patent. Patented Aug. 14, 1917.

Application filed July 1, 1916. Serial No. 107,085.

To all whom it may concern:

Be it known that I, MARK CANGEN, a citizen of the United States, residing at Brooklyn, in the county of Kings and State of New York, have invented new and useful Improvements in Arch-Supports for Shoes, of which the following is a specification.

This invention relates essentially to that class of arch supports which are adapted to be secured between the inner and outer soles of shoes to stiffen and prevent collapse of the arch.

The invention is designed to provide the inner sole with a resilient member having prongs or claws for engagement with the sole.

Heretofore in devices of this kind the arch support was fastened to the sole by means of small nails coacting with holes in the support. The objection to this method of fastening is that the nails sometimes work through the inner sole and puncture the foot of a person.

It is the object of the present invention to fasten the support to the sole by devices forming an integral part of the body of the support.

The novel features of the invention are more fully described in the following specification and claims and illustrated in the accompanying drawing in which:

Figure 1 represents a perspective view of an arch support embodying this invention.

Fig. 2 is a sectional side elevation showing the support secured between the soles of the shoe.

Fig. 3 is an inverted plan view of the inner sole.

In this drawing the letter *a* designates a resilient supporting member formed of a single strip of thin steel. This support is bowed along its length to conform to the shape of the arch portion of a shoe. The forward end *b* of the strip is pointed to form a prong for engagement with a slit *c* formed in the inner sole *d* of the shoe, by forcing the pointed end into the leather. The prong is in a line with the body of the strip so that it can be readily forced into the leather.

The other end of the strip is provided with a claw *e* having sharp bifurcated ends or prongs *f* for engagement with the leather. The ends *f* are bent at a right angle to the body of the strip so that when attaching the strip to the sole the claw end is simply

forced vertically into the material thus holding the strip firmly in place on the sole.

It will be seen that when the forward prong is in engagement with the slit and the rear claws engaged as shown it will be impossible for the device to shift laterally or move out of place on the sole.

By having the prong at one end and the peculiar shaped claw at the other the device can be easily secured to the sole, and the forward end being free to slide slightly forward in the slit will give added flexion to the soles.

As shown in the drawing when the device is in place on the inner sole of the shoe, the claw *e* will be located at the rear adjacent to the heel giving firm anchorage at the rear portion of the support, while the forward beveled pointed end is adapted to slide forward to increase the spring of the sole. By reason of the peculiar shape of the support, it can readily be arranged on the inner sole after the sole is fastened to the upper, and by having the end *b* in a line with the body *a* the device can be curved or shaped, thus adjusting it to the sole to fit a shoe with a high or low arch.

I claim:

1. An arch support of the kind described, comprising a bowed resilient body member having a prong at one end in a line with the body, and a claw bent at an angle to the body at the other end for engagement with the sole of a shoe.

2. An arch support of the kind described, comprising a bowed resilient body member having a prong at one end and a bifurcated pointed claw projecting at an angle from the other end for engagement with the sole of a shoe.

3. An arch support of the kind described, comprising a bowed resilient body member having a beveled pointed prong extending at one end in a line with the body, and a bifurcated claw with pointed ends projecting at an angle from the other end for engagement with the inner sole adjacent to the heel of a shoe.

In testimony whereof I have hereunto set my hand in the presence of two subscribing witnesses.

MARK CANGEN.
